UNITED STATES PATENT OFFICE.

THOMAS W. DE LA HUNTY, OF BUFFALO, NEW YORK.

MOLDING DEVICE.

Application filed October 8, 1921. Serial No. 506,228.

To all whom it may concern:

Be it known that I, THOMAS W. DE LA HUNTY, a citizen of the United States, residing at Buffalo, in the county of Erie and 5 State of New York, have invented a new and useful Improvement in Molding Devices, of which the following is a specification.

This invention relates to devices for use in making molds in foundries or the like.

10 In metal molding, whether by machine or by hand, it has heretofore been customary to form the drag and also the cope, if one is used, by accurately positioning the pattern with reference to the flask and after the two 15 parts of the mold have been formed, they must be accurately placed together by correctly positioning the flasks relatively to each other. The making of the mold therefore required three separate operations all 20 of which require skill and accuracy in order to produce accurate castings.

The objects of this invention are to produce a device whereby two of these three operations may be made without requiring 25 any skill or accuracy and which therefore greatly reduces the cost of making the molds; also to provide a device of this kind in which the usual flask for the drag may be eliminated; also to provide a device which 30 facilitates the placing of the cope into proper relation to the drag of the mold; also to improve the construction of devices of this kind in other respects hereinafter specified.

35 In the accompanying drawings:

Fig. 1 is a central sectional elevation of a molding device embodying the invention.

Figs. 2 and 3 are plan views thereof looking up and down respectively on line 2-3, 40 Fig. 1.

Fig. 4 is a perspective view of a cope adapted to be used in connection with the drag shown in Figs. 1 and 3.

Fig. 5 is a perspective view of the guide 45 device for enabling the drag and cope to be placed in correct relation to each other.

The drag A of the mold, as shown in Figs. 1 and 3, may be formed in an open bed of sand or in an open pit B, no flask being required for the drag. If for any reason it is desired to use a flask, for example in forming the cope, this can be done without involving any change in the invention. The mold is formed by pressing a pattern A' 55 downwardly into sand which is confined in a sand retainer C consisting of suitable side

walls which hold the sand against lateral displacement. This sand retainer is originally placed into the position shown in dotted lines in Fig. 1, above the level of the sand in the pit or bed B and is filled with sand up to the top edges of the walls. The pattern A' is preferably mounted on a plate a detachably connected, in the construction shown, to a plate d secured on a plunger D. 60 The pattern A' is first pressed into the sand confined within the sand retainer C and when the pattern has been fully embedded in the sand in the retainer, the walls thereof will engage with the pattern plate a and 65 will be pressed downwardly into the sand bed B so as to compress the sand forming the mold to the desired extent. The extent of the compression can be readily controlled by regulating the extent to which the sand retainer projects above the level of the sand in the pit B, or in any other suitable manner. 70 For example, if a small, shallow pattern is used, the sand retainer should extend above the level of the sand in the pit B to a greater 75 extent than when a large, deep pattern is used. The plunger D in the particular construction shown in the drawings, is arranged in a cylinder d' rigidly secured on the frame d² of a car or other vehicle. This car, in 80 the construction shown, is provided with wheels d³ arranged to operate on tracks d⁴ and the sand bed B is arranged between the tracks so that the car with the pattern secured thereon can be readily moved into 85 operative relation to any number of sand beds, flasks or the like arranged between the tracks.

The sand retainer C is preferably in the form of a frame of unitary structure, the frame being substantially square in the construction shown, and is preferably provided with a laterally and outwardly extending flange c which facilitates the handling of the frame. This frame serves the purpose of 95 confining the sand and preventing the spreading thereof laterally as the pattern is forced into the sand within the frame. After the pattern has been impressed into the sand, the frame is moved from the dotted 100 line position to the full line position in Fig. 1 and remains in this position until the casting is completed, thus acting as a retainer for the sand and preventing the metal which is poured into the mold from breaking the 105 sand walls of the mold and thus spoiling the casting. The means for admitting motive 110

fluid to the cylinder d' and discharging the same therefrom, to cause the piston D to move up and down as desired, may be of any usual or suitable kind, and since these means of themselves constitute no part of this invention, they are not shown.

If a cope is used in connection with the mold, this may be formed in a flask as shown in Fig. 4, in which E represents the flask and C' the sand retaining frame which corresponds with the frame C used in the drag and which, in the construction shown, is telescopically arranged in the flask. The use of this sand retainer is the same as described for the drag, the retainer being filled with the desired amount of sand, sufficient to compensate for decrease in volume occupied by the sand after compression or packing of the same. The flasks are also preferably arranged between guide tracks and the pattern for the cope may be pressed into the sand in the same manner as described for the drag.

In order to have the cope and drag register when placed together, the following construction is preferably used:

Each pattern plate a is provided with two or more locator patterns F , Figs. 1 and 2, which may be of any suitable or desired construction, those shown including one or more legs or projections f , two being shown in Figs. 1 and 2, connected by means of a connecting plate or body portion f' . These locator patterns are rigidly secured to the pattern plate a and form impressions in the sand as shown in Fig. 3, which are adapted to receive guide devices or locators G which may be of metal or other suitable material and which are provided with legs or projections g connected by a body portion or connecting plate g' . Each locator G is also provided on the opposite side of the connecting plate g' with a projection or part g^2 which is adapted to cooperate with corresponding depressions g^3 formed in the cope, Fig. 4. It will be readily understood that in the making of the mold the depressions will be formed in the drag and cope by corresponding locator patterns. When the drag is completed, locators or guide devices G are placed into the depressions formed in the drag and the projections g^2 of these locators will extend upwardly beyond the upper face of the drag. Consequently, when the cope is inverted and placed upon the drag, care is taken that the projections g^2 of the guide devices G enter into the holes g^3 in the cope. When this occurs the drag and cope will be accurately positioned with reference to each other and the mold is ready for pouring. After the pouring, the locators or guide devices can be readily removed from the sand and may be repeatedly used.

In the operation of the mold making device, it will be readily seen that since the

locator patterns are accurately positioned in correct relation on the two parts of the pattern, no care need be taken as to the position of the pattern with reference to the sand retaining member C or with reference to a flask. Consequently, the cope and drag can be formed quickly by simply bringing the pattern supporting car into operative relation to the sand pit or flask and causing the plunger D to move downwardly to press the pattern between the sand retaining walls, no accuracy being required, since the exact location of the pattern with reference to the flask or sand pit is immaterial. The only accuracy required in the making of molds by means of this device is in placing the cope upon the drag, and this is greatly facilitated by the use of the guide devices or locators. This greatly facilitates the making of molds and saves a large amount of time. Furthermore, by using the sand retaining walls with a definite amount of sand, the sand in all of the molds will be compressed to the same extent. The amount of sand required will vary with different patterns, but can readily be determined, and when this amount is once determined, no skill or judgment is required as to how much sand is needed so that the preparing of the sand beds or flasks also requires no skill.

The machine as shown is particularly well adapted for forming a large number of castings from the same pattern, but it is not intended to limit the device to such use, since the pattern plate a is detachably mounted on the plate d of the plunger so that the same can be readily removed and replaced by another pattern.

I claim as my invention:

1. The combination of a pattern consisting of two parts adapted to form the drag and the cope of a mold, plates on which said parts are mounted, projecting portions on said plates at the sides of said parts and adapted to make impressions in the sand of said cope and said drag, and means adapted to be inserted into the impressions in the drag and which is adapted to cooperate with corresponding impressions in the cope to aline said cope and drag.

2. The combination of a pattern consisting of two parts adapted to form the drag and the cope of a mold, plates on which said parts are mounted, projecting portions on said plates at the sides of said parts and adapted to make impressions in the sand of said cope and said drag, and guide devices adapted to be inserted into the impressions made in the drag and having a part extending beyond said drag and adapted to enter into impressions in the cope to aline said cope and said drag.

3. The combination of a pattern consisting of two parts adapted to form the drag

and the cope of a mold, plates on which said parts are mounted, projecting portions on said plates at the sides of said parts and adapted to make impressions in the sand of 5 said cope and said drag, and a plurality of guide devices each consisting of an integral member having parts adapted to fit into an impression in the drag for rigidly holding

said member in said impression and having a part extending beyond the upper face of 10 the drag and adapted to enter into an impression in the cooperating face of the cope, whereby said cope and drag may be accurately alined with reference to each other.

THOMAS W. DE LA HUNTY.
